UNITED STATES PATENT OFFICE.

EDWARD C. WALTER, OF NEW YORK, N. Y.

AUTOMATIC STOPPING DEVICE FOR PHONOGRAFS.

1,141,507.

Specification of Letters Patent.

Patented June 1, 1915.

Application filed November 4, 1913. Serial No 799,220.

To all whom it may concern:

Be it known that I, EDWARD C. WALTER, a citizen of the United States, residing at New York, in the county of New York and State of New York, have invented certain new and useful Improvements in Automatic Stopping Devices for Phonographs, of which the following is a specification, reference being had therein to the accompanying drawing.

This invention relates to attachments for phonographs.

The object of the invention is to provide means for automatically stopping a phonograph or a machine of like character, which means is entirely automatic in its action.

Another object is to eliminate all mechanism which requires setting by an operator.

Another object is to provide a structure which will not interfere in any way with the operation of the machine, which will be of neat appearance, and which can be manufactured at low cost.

Another object is so to construct the device that it will be self-adjusting for different lengths of needles and for different thicknesses of records.

Another object is to provide manually operated means, in addition to the automatic means, for causing arresting operation of the machine.

The invention resides broadly in the features of construction, combinations of elements, and aggroupments thereof, all as will be exemplified in the construction hereinafter set forth, and the scope of application of which will be indicated in the claims hereto appended.

While I have illustrated my invention in the accompanying drawings, by way of example, as attached to a well-known make of phonograph, it is to be understood that it may readily be adapted to other makes of machines without departing from the spirit of the invention.

In the accompanying drawings: Figure 1 is a view in plan of a phonograph showing a tone-arm, a reproducer mounted thereon, a revolving disk and record, and starting and stopping devices; Fig. 2 is a fragmentary view, in front elevation and partly in section, of the tone-arm and reproducer with the automatic device attached; Fig. 3 is a fragmentary view, in side elevation, and partly in section, of the parts shown in Fig.

2; Fig. 4 is a detail view in plan of the plates and the arms carried thereby, and showing the overlapping portion and the cushions; Fig. 5 is a fragmentary view in section of a record, showing a mechanism-controlling ridge; and Fig. 6 is a fragmentary view in plan of the under side of the top of the cabinet, showing the lower end of the starting and stopping lever, the magnet and its connections, and the motor.

The machine, preferably and as shown, is partly mounted above a baseboard or top 1 of a cabinet and the rest of the mechanism is preferably disposed beneath the base 1 and 60 inside the cabinet. A disk 2 is arranged above the base and is given a rotary movement by a motor 3 disposed beneath the base 1, and a tone-arm 4, which carries a reproducer 5, is also thus disposed. Projecting 70 above the base 1 is a lever 6 for starting and stopping operation of the motor.

The operation of the machine is as follows: A record-disk 7 provided with a spiral tone-groove 8 is placed on the disk 2, a 80 needle 9 or projection is fastened in the reproducer 5, whereupon the starting and stopping-lever 6 is moved to cause the motor to revolve the record. The reproducer 5 and tone-arm 4 are moved by hand over the 85 record 7 until the needle 9 is positioned in the outermost portion of the tone-groove 8. The revolving record, as the needle traversing the spiral tone-groove, will cause the tone-arm, and reproducer to move toward 90 the axis of the record. When the needle arrives at the end of the spiral groove, the operator stops the machine by moving the starting lever 6 in a direction opposite to that which started the motor.

Means are provided to cause the starting-lever 6 to stop the machine automatically, when the needle 9 arrives at or near the end of the spiral groove 8, and such means will now be explained:

Attached to the tone-arm 4 and at the side of the reproducer 5 (but not in the way to prevent the reproducer from being revolved or tilted) is a lug or pendant support 10, preferably of suitable insulating material. 105 Mounted on each side of this support are plates 11 provided with elongated holes or incuts 11a. Each plate 11 carries or has fulcrumed to it an arm 12, offset at its forward portion so as to occupy a position close to 110 the needle 9, carried by the reproducer 5. Attached to the forward ends of the arms 12

are cushions 13 of leather or other soft material and headed studs or stops 12^c adapted to enter the elongated holes or incuts 11^a to hold the arms 12 close to the plates 11 and 5 to limit the up and down movement of the said arms. Attached to the rear ends of the arms 12 are springs 14, which are also attached to the plates 11. These springs 14 will cause the arms 12 to be held in their 10 lowermost position when the cushions 13 are not resting on the record 7. When the arms 12 are in their lowermost position, the stops 12^c will abut against the lower ends of the elongated holes or incuts 11^a and the arms 15 will be held in a non-contacting position, and the cushions 13 will be below the plane of the point of the longest needle 9 that might be used.

While the needle is being placed in the 20 tone-groove 8, the cushions 13 abut against the record 7 first, and then the weight of the tone-arm 4 and the reproducer 5 will extend the springs 14 until the needle 9 rests in the tone-groove 8. The cushions 13 25 are held stationary by resting on the record 7 while the rear ends of the arms 12 are turning on their fulcra 12^a and are being lowered to allow the needle to rest in the tone-groove. This action allows for the use 30 of needles of different lengths or different thicknesses of records or both, and causes the stops 12^c to be moved away from the ends of the incuts 11^a.

The cushions, by resting in the tone-groove 35 or on top of the record, will have a tendency to steady and feed the tone-arm and reproducer across the record. This will permit the stylus to lie more evenly in the tone-groove and also relieve the outer side of the 40 tone-groove to some extent of the strain incident to feeding the tone-arm and reproducer across the record. The stylus being relieved of this strain is free to receive the full effect of the vibrations from the 45 tone-groove, resulting in the production of clear and natural tones.

One of the arms 12—preferably the one farthest from the needle—overlies the other arm 12 and is separated therefrom 50 (when the arms are in their lowermost position and when the stops 12^c are abutting against the lower ends of the elongated holes or incuts 11^a by a small space 12^b.) By this arrangement, the left arm 12—that 55 farthest from the needle 9—will contact with the other arm 12 whenever the left arm drops below the plane of the right arm, or whenever the right arm is raised above the plane of the left arm.

60 Electrical connection is made to the plates 11 by wires 15 which are carried through the tone-arm 4 and down into the lower portion of the cabinet to an electric battery 16 and a magnet 17. The magnet 17 upon being energized by the battery 16 (when con-

tact is made between the arms 12) moves an armature-arm 18 which is fulcrumed on a projection 19^a of the magnet-support 19. The other end of the arm 18 is notched at 18^b to form a latch in which the lower end 70 6^a of the starting-lever 6 is held when the lever is moved by the operator to the starting or running position. A light spring 20 is adapted to cause the arm 18 to latch by the lower end 6^a of the lever when being brought 75 to the starting position.

Attached to the lower end 6^a of the starting lever and also to a pin 21 on the underside of the base 1 is a spring 22 of sufficient strength to move the starting lever to the off-position when the lever is released from the notch 18^b in the armature arm 18 either by the action of the magnet 17 on the armature arm 18 when said magnet is energized, or by means now to be described:

80 A portion 18^a of the armature arm 18 projects up through the top of the cabinet and forms a means whereby the operator may, by pressing thereon, move said arm (in lieu of the magnet) to release the starting lever 6 from the notch 18^b therein.

To conserve the life of the battery 16, a break 23 in the wiring is maintained when the starting-lever 6 is at the off-position. When the lever is moved to the on-position, 95 this break 23 in the circuit is closed by the lower end 6^a of the lever 6 abutting against and moving a flat spring 24 into contact with another flat spring 25. One of the wires 15 is cut and an end fastened to each 100 of the springs 24 and 25.

When the operator moves the lever 6 to the on-position, the spring 22 is tensioned sufficiently automatically to return the same to the off-position when released, thus breaking the circuit at 23 and causing the machine to come to a stop.

105 The tone-record is provided with a depression 26, positioned at a predetermined distance from the inner end of the tone-groove 8. In lieu of this, the record may be provided with a slight ridge 27 positioned at a predetermined distance from the inner end of the tone-groove 8. The depression 26, or the ridge 27 (Figs. 2 and 5) of the record will permit the left arm 12 to drop when the needle arrives at the end of the groove, thereby forming a contact at 12^b between the two arms 12; or will cause the right arm 12 to rise to contact with the left 120 arm 12, thereby completing an electrical circuit between the battery 16 and the magnet 17 when the starting-lever 6 is at the on-position, which position is necessary to close the break 23 in the wiring at that point. 110 It will, therefore, be clear that by using a record provided either with the ridge 27, or with the depression 26, properly placed with relation to the end of the tone-groove 8, in connection with a machine equipped 115 120 125 130

- with my device, all that is necessary for the operator to do is, first, to place the record 7 on the disk, then, to start the machine by moving the starting-lever 6 to the on-position, and, finally, to place the needle 9 in the outer end of the tone-groove 8. When the record 7 has been played, the machine will, by means of my improvement, automatically stop running.
- 10 From the foregoing, it will be perceived that I have devised a structure which achieves the several objects hereinabove set forth, as well as other objects, and that it is adapted to perform its functions with certainty of operation and without in any way disturbing the operation or function of the phonograph itself.
- 15 While I have hereinabove described my invention in detail and illustrated a particular form of structure, nevertheless, it is to be understood that the disclosure is merely an exemplification of one of many possible embodiments; and, also, that the following claims are directed to the structure generally and are to be interpreted broadly, except where the details are specified therein.
- 20 What I claim is:
1. In a phonograph, a rotating member, a swinging member engaging said rotating member, and a plurality of arms and normally separated overlapping contact-points mounted on and insulated from the swinging member and movable under the influence of the rotating member to eliminate the separation between the contact-points and permit them to contact one with the other.
- 25 2. In combination, a swinging member, arms mounted thereon and insulated therefrom, and overlapping contact-points and disk-engaging cushion-elements carried by the forward ends of the arms.
- 30 3. In combination, a swinging member, a pair of overlapping arms carried thereby, cushions carried by the forward ends of the arms, and springs engaging the rear ends of the arms.
- 35 4. In combination, a swinging member, a support carried thereby, a plate at each side of the support, an arm fulcrumed to each plate, cushions carried by the forward ends of the arms, overlapping contact-points also carried by said arms, and springs connecting with the arms and the plates.
- 40 5. In combination a swinging-member, a support fastened to the member, two plates fastened to the support and insulated from one another and from the member, and arms fastened to the plates and overlapping one another and movable to abut against each other.
- 45 6. In combination, a rotating member, a swinging member, a support on the swinging member, a plate disposed at each side of the support and insulated from each other and from the swinging member, an arm carried
- 50 by each plate and one overlapping the other and normally separated from that other, cushions carried by the forward ends of the arms, and springs fastened to the arms and to the plates and operating to cause the arms to be lowered whenever free to do so.
- 55 7. The combination in a phonograph, of a support, a rotating member supported thereby and provided with a depression, a swinging member normally overlying the rotating member, and arms carried by and insulated from the swinging member and overlapping one another and normally disconnected and relatively movable to abut against one another when one of said arms drops into the depression of said rotating member.
- 60 8. The combination in a phonograph, of a support, a rotating member supported thereby and provided with a depression, a swinging member normally overlying the rotating member, a supporting-element carried by the swinging member, and arms carried by the supporting element and insulated from one another and overlapping one another and normally disconnected from each other and relatively movable when actuated by said depression to abut against each other.
- 65 9. The combination in a phonograph, of a support, a rotating member supported thereby and having a depression, a swinging member, overlapping contact points carried by the swinging member, and cushions carried by the contact points and arranged to rest on the rotating member to maintain a space between the contact points until one of the cushions drop into the depression in said rotating member thereby causing the contact points to have relative movement and to abut against one another.
- 70 10. The combination of a disk, a swinging arm, normally non-contacting contact points attached to said arm, and cushions carried by said contact points and adapted to traverse said disk and thereby hold the contact points apart, and a depression for receiving one of the cushions and thereby lowering one of said arms until the contact point carried thereby contacts with the contact point carried by the other arm.
- 75 11. The combination in a phonograph, of a disk provided with a depression, a battery, a magnet connected thereto, a swinging arm, and overlapping arms carried by said arm and connected to said battery, said arms forming a contact to complete the circuit between said battery and magnet when one of said arms drops into the depression in said disk.
- 80 12. The combination in a phonograph, of a swinging arm, self-adjusting and overlapping arms carried by the arm, cushions attached to said arms, and a rotating member upon which the swinging arm and cushions

- rest, the arms being self-adjusting to allow the swinging arm to be sustained by the rotating member in various positions of elevation.
- 5 13. The combination in a phonograph, of a swinging arm, self-adjusting and overlapping arms carried by the arm, and cushions carried by said arms, the latter being adjustable to permit relative movement of 70 said swinging arm and said arms carried thereby.
- 10 14. The combination in a phonograph, of a disk, a swinging member provided with a removable projection arranged to rest on said disk, overlapping and normally disconnected arms carried by said swinging member, and cushions on the ends of the arms, the lower edges of the cushions normally occupying a position below the removable projection but positionable in line with the extremity of the same when it and the cushions rest upon the disk and thereby holding the overlapping arms in a non-contacting position.
- 15 15. The combination in a sound-producing machine, a swinging arm, overlapping electrical contact-points mounted on the swinging arm and insulated therefrom and normally out of contact with one another, a support, a rotating member carried by the support and provided with a groove, and means carried by the rotating member for permitting the contact points to contact with one another.
- 20 16. The combination in a phonograph, of a rotatable support, a member mounted thereon and rotating therewith and provided with a depression and a groove, a motor for revolving the support and member, a starting lever for the motor, an armature-arm provided with a catch for holding the starting lever in an on-position, a spring for moving the starting lever to an off-position when released from the catch, a magnet adapted when energized to move said armature-arm to release the starting lever from the catch, a battery for energizing the magnet, a swinging arm, a holder carried by the swinging arm, a needle in the holder and arranged to travel in the groove in said member, a pair of arms, overlapping and normally disconnected electrical contact-points and cushions thereon, said arms being fulcrumed to said swinging arm and electrically connected to said battery and magnet, said cushions being arranged to rest upon the rotatable member to maintain disconnection of said contact points and be moved across the rotatable member by the needle traveling in the groove therein until one of the cushions drops into the depression in said member thereby causing one of the arms and one of the contact points to be lowered until it abuts against the other contact point and completes an electrical circuit, this causing actuation of the armature-arm and release of the starting lever from the catch therein.
- 25 17. The combination in a phonograph, of a swinging member, adjustable overlapping arms attached thereto, cushions attached to said arms, and a rotating member upon which the swinging member and cushions rest, the arms being adjustable to permit the swinging member to be held in various 75 elevated positions.
- 30 18. The combination in a phonograph, of a rotating member, a swinging member supported at one end thereby, and adjustable overlapping arms attached to said swinging member and adapted to rest on said rotating member, said arms being adjustable to permit relative movement of the swinging member and the arms carried thereby.
- 35 19. The combination in a phonograph, of a rotating member, and a swinging member supported at one of its ends thereby and provided with vertically movable overlapping contact points adapted to rest on said rotating member, said overlapping contact 90 points being vertically movable to permit relative movement of said swinging member and contact points and to thus assure their contact with said rotating member.
- 40 20. The combination in a phonograph, of a rotating member, a swinging member supported at one end thereby and movable in relation thereto, and vertically movable arms attached to the swinging member and provided with overlapping contact points 100 and cushion elements adapted to rest on said rotating member while said swinging member occupies any of a plurality of positions relatively to the rotating member.
- 45 21. The combination in a phonograph, of a swinging member, a pair of overlapping and normally non-contacting arms fulcrumed thereon, stops for holding the arms in a non-contacting position, and springs for holding said arms in said position and 110 against said stops.
- 50 22. The combination in a phonograph, of a swinging member, a support carried thereby, a plate provided with an incut at each side of the support, an arm fulcrumed on each plate, each of said arms being provided with a projection to enter one of said incuts, and springs attached to said arms and plates to hold said arms in a lowered position whereby said projections will be held 115 against the lower ends of the incuts.
- 55 23. The combination in a phonograph, of a swinging member, a support carried thereby, a plate provided with an incut fastened one on each side of the support, and an arm provided with a projection fulcrumed on each plate, the projection entering said incut to limit movement of the arm.
- 60 24. In a phonograph, the combination of a swinging member, a support carried there- 125
- 65 66. 130

- by, a plate provided with an incut and attached one on each side of said support, a pair of overlapping and normally non-contacting arms each fulcrumed on a plate, a
- 5 projection on each arm adapted to enter an incut, and springs attached to said arms and plates and adapted to hold said projections against one end of said incuts and thereby hold said arms in a non-contacting position.
- 10 25. In a phonograph, the combination of a swinging member, a support carried thereby, a plate fastened one on each side of the support, said plates each being provided with an elongated hole, an arm fulcrumed on each plate and provided with a projection adapted to enter the hole of the plate to which the arm is fulcrumed, springs attached to said arms and said plates and
- 15 20 adapted to hold said projections against the

ends of said holes, and a rotating member upon which said arms rest to move said projections away from the ends of the holes.

26. The combination in a phonograph, of a revolving disk, a swinging member, a 25 pair of arms provided with overlapping and normally non-contacting contact points and cushion elements attached to said swinging member, said cushions being adapted to rest upon said disk, and said disk 30 having means for causing one of the said arms to move relatively to and contact with the other arm.

In testimony whereof I affix my signature in presence of two witnesses.

EDWARD C. WALTER.
